UNITED STATES PATENT OFFICE.

OLIVER H. HICKS, OF CHICAGO, ILLINOIS.

PAPER RECEPTACLE.

SPECIFICATION forming part of Letters Patent No. 367,298, dated July 26, 1887.

Application filed March 12, 1887. Serial No. 230,745. (No model.)

To all whom it may concern:

Be it known that I, OLIVER H. HICKS, a citizen of the United States, residing at Chicago, in the county of Cook and State of Illinois, have invented a certain new and useful Improvement in Paper Receptacles; and I hereby declare the following to be a full, clear, and exact description of the same.

My invention relates to an improvement upon the construction of paper receptacles shown in Letters Patent of the United States No. 351,980 granted to me on the 2d day of November, 1886; and it is the object of my present construction, like that in my said former patent, to dispense with a separate cover for the receptacle and provide other more desirable and effective means for closing it.

To this end my improvement consists in the construction hereinafter set forth and claimed.

20 In the drawings, Figure 1 is a perspective view of the paper receptacle opened and provided on one side with a bail or handle, the ends of which form the clamps by insertion through openings in the opposite side and 25 bending them; and Fig. 2 is a similar view showing the receptacle closed and clamped by means of my improvement.

A is the coverless receptacle, formed by folding a continuous sheet of paper, as described 30 in my aforesaid Letters Patent, to produce the flat base *r* and rectangular shape represented, the free or loose corners *q* and *q'* formed by the folding being lapped one upon the other, as shown, over the opposite sides of the receptacle and secured in any desired manner.

35 B is the bail or handle, composed of some material that possesses the quality of pliability and will remain in any form and position to which it is bent, such as wire. The material 40 forming the handle is bent to the angular shape illustrated, and the opposite ends are inserted through one side of the open receptacle near its upper edge to afford strips or strands *p*, which project into the receptacle and are bent 45 upward, as shown, or down against the inner surface of such side.

The bending of the strips or strands *p*, as

aforesaid, subserves a twofold purpose, one being to secure the handle from withdrawal and consequent possible loss in the handling 50 or shipment of the article prior to its use as a receptacle, and the other to prevent the strips or strands from forming an obstruction in nest- 55 ing the receptacles, it being necessary, or at least desirable, to nest them for shipment.

To close the receptacle, and thus effectively shield its contents from exposure, the opposite sides are compressed together, the ends toward their upper edges being at the same time forced inward to assume the shape represented in Fig. 2, and the strips or strands *p* on the handle previously straightened are caused to penetrate the opposite side of the receptacle, preferably by being inserted through respectively adjacent openings *o* and 60 *o'* bent back over the contiguous edges of the opposite sides to clamp them together.

The bail and clamps serve to secure or assist in securing against the respective sides of the receptacle the folded corners, which also re-enforce the article and produce, if the insertion of the clamps and bail be at the points, as represented in Figs. 1 and 2, quintuple thicknesses of the paper, whereby sufficient resistance is afforded against tearing out the bail 70 and clamps by the weight of the contents.

What I claim as new, and desire to secure by Letters Patent, is—

The combination of a receptacle, A, formed of a folded sheet of paper having the corners 80 folded and secured upon the receptacle, and a handle, B, secured to one side of the receptacle and extending at its extremities to afford clamping strips *p*, whereby the receptacle may be closed by bringing together the sides thereof toward the opening and secured in closed condition by extending the extremities forming the strips *p* through the opposite side and fastening them, substantially as described.

OLIVER H. HICKS.

In presence of—

J. W. DYRENFORTH,
DOUGLAS DYRENFORTH.
